AUTOMATIC FIRE ALARM SYSTEM

Hiram D. Scott, Bartlesville, Okla., assignor of
one-half to Frank M. Small, Bartlesville, Okla.

Application October 5, 1934, Serial No. 747,102

9 Claims. (Cl. 179—5)

This invention relates to improvements in fire alarm systems of the automatic type and the object thereof is to provide an arrangement to utilize the conventional equipment of panel dial systems to cause the automatic sending of a signal from a residence, factory or other point at which a fire originates to the fire station.

A further object of the invention is to provide an arrangement utilizing the wires of the conventional telephone system for indicating at the fire station the exact location of the point of origin of the fire.

Another object of the invention is the provision of a system including a thermostatically controlled signalling device, which, at the initiation of a fire, is set in operation and through automatic dialing operations, first establishes a connection through the telephone exchange into the fire station and, after such connection has been established, performs further signalling operations transmitted to the fire station at which point the incoming signal operates a related signal device to notify the fire station attendants of the location of the fire.

A still further object of the invention is the provision of an automatic fire alarm system utilizing the wires of the conventional telephone system, but which does not interfere in the least with the normal operation of the telephone in the residence, factory or other place where the system is installed.

With the foregoing objects outlined and with other objects in view which will appear as the description proceeds, the invention consists in the novel features hereinafter described in detail, illustrated in the accompanying drawings, and more particularly pointed out in the appended claims.

In the drawings,

Fig. 1 is a diagrammatic view of the complete installation showing the connections between the local installation, the automatic telephone exchange and the fire station.

Fig. 2 is a detail diagrammatic view of the electrical circuit at the local installation.

Fig. 3 is a front elevation partly broken away and in section of the signalling wheel device at the local installation.

Fig. 4 is an end view of Fig. 3.

Fig. 5 is a partial plan view of a signalling device.

Fig. 6 is a longitudinal sectional view of the signalling wheel.

Fig. 7 is a vertical section on the line 7—7 of Fig. 3.

Fig. 8 is an end view similar to Fig. 4, showing the release armature in attracted position.

Fig. 9 is a lineal development of the helix on which the signalling pins are arranged along the signalling wheel.

Fig. 10 is a diagram of the electrical circuit at the fire station.

Fig. 11 is a front elevation of a modification of the signalling device.

Fig. 12 is an end view of the arrangement shown in Fig. 11.

Fig. 13 is an enlarged vertical section taken transversely through the feed screw and showing the carriage and related parts in elevation.

Fig. 14 is a further enlargement in section through the feed screw and carriage showing the adjustable feed member.

Referring to the drawings in detail, and in particular to the diagrammatic representation of the entire system illustrated in Fig. 1, A indicates the part of the device located at the residence, factory, plant or other structure in which the system is installed. For convenience in future reference, this part of the system will hereinafter be referred to as the "local installation".

B indicates diagrammatically the automatic exchange of a panel dial telephone system and C illustrates the part of the system located at the fire station.

The part of the apparatus constituting the local installation is connected by branch conductors 10 and 11 with the usual line wires 12 and 13 leading from the exchange B to the local telephone set 14. The conductor 10 is connected with the coil of a release magnet 15. The opposite end of the coil of which latter is connected with one terminal of a thermostat 16 over a wire 17 and the opposite terminal of the thermostat is connected over a conductor 18 to one of the terminals of contact device designated generally at 20.

Normally the two contact members constituting the device 20 are in engagement with each other and the other terminal of the contact device 20 is connected with the branch conductor 11.

The thermostat 16 is of the normally open type but upon occurrence of an abnormal temperature rise in the vicinity thereof, it operates to close and thereby connect the conductors 17 and 18 and close the circuit over the branch conductors 10 and 11 through the coil of the release magnet 15 and the contact device 20 and wheel 21.

It will be understood that a suitable type of thermostat will be selected and this is preferably so constructed as to close the circuit when the

temperature in the room or other place in which it is located rises ten degrees in one minute or fifteen degrees in three minutes.

A manually operated switch 23 is shunted 5 against the conductors 17 and 18 and is adapted for use in testing the alarm system and for other purposes.

The armature 24 of the electromagnet 15 is pivotally mounted and cooperates with the signalling device to control the operation of the latter as will be hereinafter more clearly described. The terminal of the armature 24 is provided with a projection 25 cooperating with the contacts 26 and 27 whereby when the armature 15 is attracted the projection 25 closes the contacts 26 and 27. The conductors 28 and 29 forming part of the electric supply system for the residence, factory or other place of installation, are connected, one with a transformer 30 and the other with the contact 26. The other contact 27 is connected with the other terminal of the primary winding of the transformer. The secondary winding of the transformer is connected over conductors 31 and 32 with a bell or other 25 audible local alarm device 33 which is thus automatically set in operation by the local current supply upon actuation of the armature 24.

The signalling device is preferably located in a suitable protective casing and includes a signalling wheel 35 coacting with the contact members 26 and 27 and controlled by the releasing armature 24 as will be hereinafter more fully described. In the embodiment of the invention herein illustrated the signalling wheel is driven 30 by a spring motor including a supporting shaft 35a, a coil spring 35b, a ratchet wheel 35c and a pawl 35d. The ratchet wheel 35c is rigidly secured to the shaft 35a but is rotatably mounted in bearings 35e provided internally of the wheel 35. One end of the spring 35b is fastened to the shaft 35a and the opposite end to the wheel 35 whereby when the spring is tensioned the latter acts to revolve the wheel 35. The shaft 35a is rotatably supported in a suitable frame 36 and 40 the end of the wheel 35 opposite the ratchet and pawl device 35c, 35d is provided with a stub shaft 35f which is also rotatably mounted in the frame 36 and supports the wheel 35 for rotation therein.

The stub shaft 35f is provided at its end with 45 gear teeth 35g meshing with a gear wheel 37 which latter is provided with a smaller pinion 38 meshing with the internal gear teeth 39 of a cam ring 40. At one point the rim of the cam ring 40 is interrupted as indicated at 40a and 50 when the signalling device is in its normal or inoperative position as shown in Fig. 4, the angular arm 24a of the armature 24 is engaged in a recess 40a and is held therein by a spring 24b. The armature is pivotally mounted on the supporting frame 36 in operative relation to the magnet 15. Intermediate the gear wheel 37 and the pinion 38 a stop 41 is arranged which engages with the angular arm 24a and arrests the rotary movement of the signalling wheel 35 after the latter 55 has made a predetermined number of revolutions as will hereinafter fully appear.

The contact device 20 includes a relatively stationary contact member 20a and a movable contact member 20b both of which are secured to 60 a supporting lever 42 pivotally secured at 42a to a carriage 42b slidably mounted on guide rods 42c secured in the supporting frame 36. A feed screw 42d is rotatably mounted in the frame 36 and the curved portion 42e of the lever 42 is 65 threaded correspondingly with the screw 42d and

is normally maintained in engagement therewith by a spring 42f. When the lever 42 is swung downwardly against the tension of the spring 42f, the threaded portion 42e thereof is disengaged from the feed screw 42d and the carriage may 5 be freely moved from end to end of the guides 42c. The depression of the lever 42 also swings the contact member 20b out of operative relation with the wheel 35.

Rotary motion of the signalling wheel 35 is 10 transmitted to the feed screw 42d by gear wheels 43 and 43a whereby the carriage 42b is moved axially during rotation of the signalling wheel.

One of the purposes of the signalling wheel 35 is to send a number of impulses over the telephone lines 12 and 13 corresponding with the calling number of the fire station C and for purposes of illustration, the number "300" has been arbitrarily selected. The impulses are produced by interruptions in the circuit when the contact members 20a and 20b are separated and for this purpose the wheel 35 which is in the form of a hollow cylinder is formed externally with a plurality of groups of pins or projections arranged about a helical path the pitch of which corresponds with the pitch of the thread of the feed screw 42d. The pins are so arranged that as the signalling wheel revolves and the carriage 42b is moved axially thereof, said pins are successively engaged with the relatively movable contact member 20b and disengage the latter from the stationary contact 20a thereby interrupting the circuit.

A partial development of the helically arranged pins on the signalling wheel 35 are illustrated on the fragmentary lineal development of said wheel illustrated in Fig. 9. According to the selected number "300", three pins 44 are arranged in the first group and ten pins each in the two successive groups 45 and 46. Thus as the signalling wheel revolves and the telephone lines 12 and 13 are connected over the contact members 20a and 20b, first, three circuit breaks will occur as the pins of the group 44 engage the contact member 20b and the panel dialing system of the exchange B will respond by stepping up the selectors and connections three times. Thereafter, the selectors will be stepped across ten times by the pins 45 and again ten times by the third group of pins 46. The operation is the same as a person dialing "300" on an automatic dial telephone and in order to regulate the speed of the signalling wheel in accordance with the timing of the usual dialing operations of conventional systems, a suitable speed governor 47 is connected with the feed screw 42d.

Following the group of contact pins 46, additional groups 48 and 49 are arranged on the signalling wheel and the pins of these two last mentioned groups correspond with the identifying 60 number of the residence, factory or other place at which the apparatus is installed. It will be noted, however, that between the groups of pins 46 and 48 a relatively wide space 50 is provided and this is of importance as it is designed to allow ample time for the ringing machine in the exchange to complete its cycle which is generally one ring every second and a half second interval between the rings. Unless the space 50 is of sufficient length the succeeding group of pins 48 70 and the circuit interruptions caused thereby would cause the selectors of the exchange to complete "300" and stack up.

For purposes of illustration a number "72" has been arbitrarily selected for the identification of 75

the local installation A and groups of pins 48 and 49 in passing over the movable contact member 20b cause interruption of the telephone circuit a corresponding number of times and periods and these interruptions are transmitted to and detected at the fire station C and indicate the point at which the fire has originated, as will be hereinafter more fully described.

At a point following the last group of pins 49

10 a raised surface 51 is provided on the signalling wheel which engages the contact member 20a following the transmission of the two numbers "300" and "72" and opens the telephone circuit for a period sufficient to cause an interruption in the

15 operation of the magnet 15 and during this period the entire telephone equipment restores itself to normal. During this period, all of the equipment at the fire station C is also restored to normal condition with the exception of the

20 signalling device therein identifying the local installation at which the fire has started, as will hereinafter more fully appear. The signalling wheel 35 continues to operate, however, under the driving force of the spring 35b and the cycle

25 of operation above described is repeated. For this purpose a second series of groups of contact pins 44, 45, 46, 48 and 49 and a further raised surface 51 are provided which effect a repetition of the calling and signalling operations. Four

30 series of groups of pins and raised surfaces are preferably provided as this is the number of times which the conventional fire alarm system ordinarily repeats.

It will be understood that rotation of the signalling wheel 35 is initiated by the spring 35b when the armature 24 is attracted incident to closing the circuit of the magnet 15 across the thermostat 16, the contact members 20a and 20b being initially in engagement with each other as illustrated in Fig. 2. Actuation of the armature 24 disengages the angular extremity of the arm 24a from the recess 40a and the stop 41 thereby permitting the signalling device to operate.

At the end of the four series of groups of contact pins 45, 46, 48 and 49 and the raised surface 51 an elongated raised surface 52 is provided on the signalling wheel which engages the contact member 20b and opens the circuit for a longer period. The ratio of the gear wheels 35g, 50 36, 38 and 39 is so selected that when the contact member 20b reaches the terminal raised surface 52, the cam disk 40 has completed one revolution and the angular extremity of the arm 24 entering the recess 40a under the influence of the spring 24b engages the stop 41 which latter arrests the rotary movement of the signalling wheel 35.

At the fire station the telephone wires 54 and 55 are connected with normally closed contact members 56-57 and 58-59, the current passing through said contacts over conductors 60 and 61 to the slow release relay 62. A condenser 63 is interposed in the conductor 60 but, as will be understood, the ringing machine of the telephone system supplies alternating current and this current passes the condenser and operates the relay 62 whereas direct current will not pass said condenser. The alternating current energizes the relay 62 attracting the armature 64 and closing the contact pairs 65-66 and 67-68. The closing of the contact 65-66 short-circuits the relay 62 over the conductors 69 while the closing of the contact 67-68 closes the circuit of a relay 70 connected by conductors 71 and 72 with a local current source 73. The relay 62 is of the retarded

type and therefore affords ample time to assure actuation of the relay 70. The armature 74 of the relay 70 actuates a group of contact members designated at D in which the contact members 56 to 59 are included. Upon actuation of the set 5 of contacts D, the contact members 75 and 76 close a circuit from the positive pole of the current source 73 over the restoring button 77 through a conductor 78 to the conductor 18a, contact members 75 and 76 and over a conductor 10 79 to the conductor 12, relay 70, conductor 71, thereby locking the relay 70 in energized condition. The contact member 58 cooperates with a contact member 80 and the contact member 56 cooperates with contact member 81 when the 15 group of contacts D is actuated and in this manner a circuit is closed from the conductor 54 over the contact members 56 and 81, conductor 82, one side of condenser 83, the coil of the relay 84, conductor 85, other side of condenser 83, contact members 80 and 58 and the conductor 55. The relay 84 acts as a receiver with condenser 83 in parallel with the winding thereof and it does not operate until the groups of pins 48 and 49 pass the contact member 20b, but when the 20 current is interrupted by the passage of the said pins the armature 86 of the relay 84 is actuated, first, seven times as the group of pins 48 passes thereby causing the selector 87 to step up seven times and, when the two contacts 49 pass the contact member 20b the selector 87 steps across two times. The impulses are transmitted to the selector 87 in response to those received by the relay 84 over a conductor 88 and a pair of contacts 89 which are actuated at each attraction of the armature 86, a conductor 90, a resistance 91, a pair of contacts 92 which are closed when the group D is operated and a conductor 93 leading back to the selector 87. This operation of the selector establishes the circuit 7-2 in accordance 30 with the number of impulses received over the selector 87 and the connector 94.

The circuit identified as 7-2 in the fire station is the one which includes the visible signal on the switch board associated therewith. When the 45 conductors 95 and 96 are closed through the connector 94, the following circuit from the positive pole of the local source of current 97 is closed, conductor 95 including the resistance 95a, connector 94, conductor 96, relay coil 98 and conductor 99 to the negative pole of the current source 97. The closing of this circuit energizes the relay 98 and the contact members 98a thereof being closed a second circuit from the conductor 96 over the contact members 98a to the 50 coil 100 of a second relay and over the conductor 101a to the negative pole of the current source 97 is completed. The relay 100 is energized and the contact members 102 thereof are moved into contact and another circuit leading from the positive pole of the current source over the conductors 95 and 96 through the contact members 98a, relay coil 100, contact members 102 and conductor 103 to the conductor 101a leading to the 55 negative pole of the current source is completed.

The line lamp constituting the fire station indicating device 101 is interposed in the conductor 101a and is illuminated when the circuit of this conductor is closed, while the pilot lamp 104 is interposed in the conductor 103 and is lighted 70 when the circuit over this conductor is closed.

In this manner the line lamp 101 on the indicating board at the fire station related to the signalling wheel 35 which has been set in operation by the release of the associated thermostat 75

16 as well as the pilot 104 are illuminated. In order to restore the circuit to normal the restoring button 11 is manually actuated thereby interrupting the circuit of the relay 70 and permitting 5 all of the contact members of the group D to return to initial position.

An audible alarm device 110 is located at the fire station and is supplied with current from a local source 111 over conductors 110a and 110b 10 when the two contacts 112 are engaged as when the armature 14 is attracted.

As stated in the foregoing when the signalling wheel 35 moves to a position where the contact members 20a and 20b are separated by the long 15 raised surface 51, all equipment in the telephone office is restored to normal, but the calling operations are repeated three more times owing to the provision of the multiple series of groups of pins 45, 46, 48, 49 and the raised surfaces 51. When 20 the contact member 20b reaches the final raised surface 52, the disc 40 will have completed one revolution and the magnet 15 being de-energized permits the arm 24a to enter the recess 40a and engage and arrest the stop 41.

25 Referring to the modification of the invention illustrated in Figs. 11 to 14, the signalling wheel 35 corresponding in construction to that above described, is supported on a shaft 121 geared by a worm and worm wheel 122 with the shaft 123 30 of a speed governor 124.

The shaft 121 is driven from a spring motor 130 actuating a gear wheel 125 through a train of gears 126, 127 and 128. The release magnet 15 is the same as that above described in connection 35 with Fig. 1, and the contacts 26 and 27 controlling the local alarm 33 are also the same and the detail description thereof will not, therefore, be repeated. In the modification, however, an armature lever 124a is pivoted at 129 and provided 40 with a recess 131 normally coacting with the pin 132 on the gear wheel 126 to lock the drive mechanism for the signalling wheel 120 against operation prior to a fire. In the case of the construction described, the ratio of the gear 45 wheels 126 to 128 is suitably chosen whereby the pin 132 enters a second recess 133 after the complete operation of the signalling device and the drive mechanism is thereby arrested.

50 The conductors 11 and 18 (Fig. 2) are connected respectively with spring contact members 134 and 135, which latter in their normal position engage one another and thereby close the circuit across the conductors 11 and 18. The members 134 and 135 are supported in a holder 136 pivotally mounted on a shaft 137 supported on posts 138 fixed in the carriage 139. The holder 136 is provided with an arm 140 having a knob-like end and also a spring 141.

The carriage 139 is provided with a bore 142 55 which is slidably mounted upon the feed screw 143 which latter is extended at one end to form the supporting shaft for the gear wheels 126 and 127. The movement of the carriage 139 is confined by a suitable guide 144 engaging recesses 60 provided in the carriage.

The feed shaft 143 is provided with two sets of screw threads 145 and 146, the first being adapted to effect the feed movement of the carriage during the operation of the apparatus and 65 the other thread, which is of steeper pitch, being adapted to effect the rapid return of the carriage, the two threads being oppositely pitched. The carriage 139 is provided with a spring-actuated pin 147 having a handle 148 at the outer end 70 thereof and a thread-engaging member 149 at

the inner end. The medial portion of the thread-engaging member 149 is provided with a projection 150. The return thread 146 is of greater depth than the said thread 145 and when the pin 147 is adjusted to engage the thread-engaging 5 member 149 therein, the carriage, due to the pitch of the thread 146 and the direction of rotation of the shaft 143, is returned to its initial position at the left end of the screw. In the normal position of the apparatus, that is to say, when it is 10 set for operation in response to the outbreak of a fire, the pin 147 is adjusted by means of the handle 148 so that the projection 150 engages in shallow groove of the feed screw 143.

Immediately above the guide 144 a guide rail 15 15 151 is located and at the ends thereof curved guide arms 152 are arranged. In moving from right to left during the return movement of the carriage 139, the arm 140 slides along the top of the guide rail 151 retaining the pivoted brush 20 holder 136 together with the contact members 134 and 135 in upwardly tilted and inoperative position out of contact with the pins of the wheel 35. However, as the arm 140 engages under the left hand curved guide member 152 it is depressed 25 thereby and engaged beneath the guide rail 151 which latter during the feed movement of the carriage, tilts the brush holder 136 into operative position, the spring 141 being retained in compressed condition. When the carriage has completed 30 its movement toward the right, the spring pressing against the top of the guide 144, lifts said arm from under the curved guide rail 151 and thereafter the springs rest on top of the rail 151 for return of the carriage to initial position. 35

At the initiation of operation of the modified construction the electromagnet 15 is energized the same as in the construction first described upon the occurrence of a fire and upon actuation of the arm 124a, the pin 132 is released and the 40 drum wheel 120 is set in operation by the spring motor 130. Under these conditions, the contact holder 136 being depressed by engagement of the arm 140 under the guide rail 151, the finger 157 of the upper contact member 134 is disposed 45 in the path of the pins of the signalling wheel 35 and actuated thereby.

At the end of the travel of the carriage, the thread-engaging member 149 coacting with the return thread 146 returns the carriage to initial 50 position at the left end of the cylinder but in the reversal of movement of the carriage at the right end of travel, the arm 140 passing the end of the rail 151 is raised by the spring 141 and the contact holder 136 is tilted upwardly to inoperative position. As the carriage comes to its initial position at the left end, the contact holder is drawn downwardly to operative position by engagement of the arm 140 with the guide 152 but the break strip 155 engaging the finger 140 60 separates the contact members 134 and 135 thereby restoring the circuit 10-11 to open condition. 65

It will be understood that the governor 124 is so adjusted as to regulate the speed of the signalling wheel 35 that the impulses produced by the actuation of the contact members 134-135 is in accordance with that of conventional telephone systems

It will also be understood that the ratio of gearing of the gear wheels 125 to 128 is such that the 70 wheel 35 revolves throughout a period corresponding in time to that required by the movement of the carriage 139 from left to right and to its return position beneath the guide 152 at which point the pin 132 enters the recess 133 and move- 75

ment of the wheel is arrested with the break strip 155 engaging the finger 157 and retaining the circuit 10-11 in open condition.

- A structural point of importance to be noted 5 in connection with both forms of the invention consists in that at the conclusion of the four repetitions of the signal produced by the signalling wheel, the latter comes to rest at a point where the contact members associated with the 10 wheel 35 are separated one from the other, and thus the circuit across the branch conductors 10 and 11 is left open and the telephone 14 at the local installation is in condition for service use. This is accomplished in connection with the form 15 of invention first described by arresting the movement of the wheel 35 when the raised strip 52 is disposed on the contact member 20b.

In the second form of the invention this purpose is served by the relatively long strip 155 at 20 the left end of the wheel which engages and lifts the finger 157 when the contact holder is restored to initial position.

From the foregoing it is believed that the construction, operation and advantages of the invention 25 may be readily understood by those skilled in the art, and it is apparent that changes may be made in the details disclosed, without departing from the spirit of the invention, as expressed in the claims.

30 What I claim and desire to secure by Letters Patent is:

1. In an automatic fire alarm system, a local installation, a fire alarm station, a panel dial telephone system, said telephone system including 35 telephone lines leading to the local installation and to the fire station and an automatic exchange adapted to connect the two lines in response to signal impulses sent thereover, said local installation including a motor-operated signalling device, thermostatically controlled release means associated with said signalling device, and means actuated by said signalling device to connect the 40 lines leading from the local installation with the exchange and to transmit the calling signal of the fire station whereby to establish a connection over said lines from said local installation through the exchange to the fire station, said signalling device including a rotatable wheel having two series of signalling elements thereon, the first 45 series corresponding to the signal of the fire station and the second series corresponding with the identifying signal of the local installation, and a relatively wide space between the several series of signalling elements adapted to afford a 50 relatively long time interval between the termination of the sending of the first series of signals and the initiation of the sending of the second series of signals.

2. In an automatic fire alarm system, a local 60 installation including telephone lines of a panel dial telephone system, a motor driven signalling wheel, a thermostatic device and means actuated in response to operation of the thermostatic device to connect said telephone lines with said 65 signalling wheel and to release the latter whereby it may be operated by the motor drive, a plurality of series of signalling elements distributed over the circumference of the signalling wheel, a relatively wide space between the several series of 70 signalling elements affording a sufficiently long time interval therebetween to permit the standard ringing machine of said telephone system to function in the normal manner and to then restore itself.

75 3. In an automatic fire alarm system, a local

installation, a fire alarm station, a panel dial telephone system, said telephone system including telephone lines leading to the local installation and to the fire station and an automatic exchange adapted to connect the two lines in response to signal impulses sent thereover, said local installation including a motor operated signalling device, thermostatically controlled release means associated with said signalling device, means to connect the lines leading from the local installation with the exchange, said signalling device including a rotatable element having two series of signalling members thereon, the first series corresponding to the signal of the fire station and the second series corresponding with the 15 identifying signal of the local installation, the several series of signal members being relatively arranged on the rotatable element to afford a time interval between the termination of the first series of signals and the sending of the 20 second series, whereby the ringing equipment of the automatic exchange may restore itself to normal.

4. In an automatic alarm system, a local installation including telephone lines leading through 25 an automatic telephone exchange to an alarm receiving apparatus, said local installation including a signalling element, means for setting said signalling element in operation and for connecting said signalling element to said telephone lines, said signalling element including 30 two series of signalling members, said series being so spaced from each other as to afford a time interval therebetween sufficient to permit the standard ringing equipment of the automatic exchange 35 to restore itself.

5. In an automatic alarm system, a local installation including telephone lines leading through an automatic telephone exchange to an alarm receiving apparatus, said local installation 40 including a signalling element, means for setting said signalling element in operation and for connecting said signalling element to said telephone lines, said signalling element including a first series of signalling members adapted to establish 45 a connection from said local installation through said exchange to said receiving apparatus, a second series of signalling members adapted to transmit the identifying signal of said local installation directly to said receiving apparatus, 50 said first and second series of signalling members being so spaced from each other as to afford a time interval therebetween sufficient to permit the standard ringing equipment of said exchange 55 to restore itself.

6. In an automatic alarm system, a local installation including telephone lines leading through an automatic telephone exchange to a receiving apparatus, said local installation including a signalling element, means for setting 60 said signalling element in operation and for connecting said signalling element to said telephone lines, said signalling element including a first series of signalling members adapted to establish a connection from said local installation through said exchange to said receiving apparatus, a second series of signalling members adapted to transmit the identifying signal of said local installation directly to said receiving apparatus, 65 said first and second series of signalling members being so spaced from each other as to afford a time interval therebetween sufficient to permit the standard ringing equipment of said exchange 70 to restore itself and automatic means cooperating with said receiving apparatus responsive to said 75

first series of signalling members whereby said receiving apparatus is put in condition to receive and register said identifying signal transmitted by said second series of signalling members.

- 5 7. In an automatic alarm system, a local alarm mechanism connected by telephone lines to an automatic telephone exchange, a standard ringing machine cooperating with said exchange, telephone lines leading from said exchange to an alarm receiving apparatus including a relay cooperating with said receiving apparatus and actuated by said ringing machine to complete a circuit over said telephone lines from said local mechanism to said receiving apparatus.
- 10 8. In an automatic alarm system, a local alarm mechanism including telephone lines leading through an automatic telephone exchange to an alarm receiving apparatus, a standard ringing machine cooperating with said exchange and said receiving apparatus, said local mechanism including a signalling element, means for setting said signalling element in operation and for connecting it to said telephone lines, said signalling element including successive series of signalling members, said series being so spaced from each other as to afford a time interval therebetween sufficient for said ringing machine to func-

tion in the normal manner and to then restore itself, a relay actuated by said ringing machine to establish a circuit including said local mechanism and said receiving apparatus.

- 5 9. In an automatic alarm system, a local alarm mechanism connected to the telephone lines of an automatic telephone exchange including a standard ringing machine and thence to an alarm receiving apparatus, said alarm mechanism including a first series of signalling members adapted to establish a connection from said alarm mechanism through said exchange to said receiving apparatus, a second series of signalling members adapted to send signals to be registered by said receiving apparatus, a space between said first and second series of signalling members of such length as to permit said ringing machine to function in the normal manner and to restore itself prior to the transmission of said second series of signals, a relay cooperating with said receiving apparatus and actuated by said ringing machine to establish a circuit over said telephone lines including said alarm mechanism and said receiving apparatus over which said second series of signals may be transmitted to be registered by said receiving apparatus.
